UNITED STATES PATENT OFFICE.

HERMANN ZEITZ, OF HAMBURG, GERMANY, ASSIGNOR TO SCHMIDT'SCHE HEISSDAMPF-
GESELLSCHAFT M. B. H., OF CASSEL-WILHELMSHÖHE, GERMANY, A CORPORATION
OF GERMANY.

BLOWER DEVICE FOR CLEANING TUBES.

1,183,417.

Specification of Letters Patent.

Patented May 16, 1916.

Application filed November 30, 1914. Serial No. 874,940.

To all whom it may concern:

Be it known that I, HERMANN ZEITZ, a subject of the Emperor of Germany, residing at Hamburg, Germany, have invented
5 certain new and useful Improvements in Blower Devices for Cleaning Tubes, of which the following is a specification.

10 My invention relates to blower devices for removing soot, ashes, and the like from boiler tubes and particularly to those of the type in which the distance of the nozzle orifice from the tube plate can be varied in such a manner that the jet serving as the cleaning agent passes over the tube ends in a 15 spiral path.

My invention resides in certain details of construction as will be more particularly set forth in the description and claims which follow.

20 The object of my invention is to make devices of the character specified more efficient as well as more convenient and certain in operation.

25 My invention will be better understood by referring to the drawings in which—

Figures 1 and 2 show vertical sections through blower in the inoperative and operative positions respectively, and Fig. 3 a modification of a spindle with two nozzle 30 orifices.

The blower constructed according to the present invention (see Figs. 1 and 2) comprises a casing *b* arranged in fluid-tight relation to the tube *a* and having a flange *b'* 35 by means of which it may be secured by screw bolts to the appropriate wall of the boiler. The casing *b* is further provided with a branch *b*², through which steam is supplied and with a cover *f* to which an internally threaded boss *g* is connected by the arms *f'*. The casing *b* with its cover *f* and boss *g* serves to receive and guide a spindle *d* the rear end of which is threaded to correspond with the threads of the boss *g*. The 40 spindle *d* is solid in the neighborhood of its threaded portion but for the remainder of its length is hollow and is provided near its rear end of the hollow portion, with a collar *d'*, which is formed after the manner of 45 a conical valve; when the spindle *d* has been screwed back to its full extent, that is to say, when it assumes the position shown in Fig. 1, the collar *d'* seats against a corresponding surface *f*² (see Fig. 2) provided 50 on the cover *f*. Behind the collar *d'* the

hollow spindle is provided with a few holes *x'* which allow the steam or other fluid used for cleaning the tubes to pass from the casing *b* into the interior of the hollow portion *x* of the spindle *d* except when the collar *d'* 60 is in the position shown in Fig. 1.

Stuffing boxes *h* and *c* are provided in the cover *f* and casing *b* respectively to prevent leakage from the casing along the spindle. The gland of the stuffing box *c* is secured in 65 position by a ring *c'* which is screwed or otherwise adjustably inserted in the casing. At its front end, the spindle *d* is provided with a cap *k* which is protected by the tube *a* when the spindle is withdrawn to its inoperative position. If the spindle *d* is rotated 70 from this position, it advances and the cap or nozzle *k* projects from the tube *a* while simultaneously communication between the interior of the casing and the hollow portion of the spindle *d* is established so that the fluid serving for cleaning purposes can enter the spindle through the holes *x'* and escape through the orifice *k'*.

The cap *k* is provided either with a single 80 orifice as in Figs. 1 and 2, or with a plurality of orifices, preferably two, *k'* and *k*², as in Fig. 3, arranged at different angles to the axis of the spindle *d*. The longer the path traversed by the jet issuing from the 85 nozzle, the greater will be the distance from the axis of the spindle *d* produced, at which it will strike the opposite tube plate or the smoke tubes associated therewith. The steam jet therefore will strike the smoke 90 tubes which are farthest away from the central axis of the spindle, *d*, during the beginning of the forward movement of the spindle, *d*, those tubes less remote being next affected as the spindle is fed forward until 95 finally when the spindle is fed forward to its full extent, the steam jet will strike those tubes in the immediate neighborhood of the axis of the spindle *d* produced.

If only one orifice *k'* is provided in the 100 cap *k*, the travel of the spindle *d* must approximately correspond to the distance between the front and rear walls of the combustion chamber since the orifice *k'* is arranged at such an angle that the jet of steam issuing from it strikes the outermost smoke tubes at the beginning of the forward movement of the spindle *d*. The travel of the spindle, however, can be considerably 105 reduced, if two or more orifices, such as *k'* 110

k^2 are arranged at different angles to the axis of the spindle, and the entire group of smoke tubes concerned can then be cleaned in a shorter time.

- 5 If the blower is used for a single-ended smoke-tube boiler it may be inserted in a tube passing from the rear plate of the boiler to the rear wall of the combustion chamber, while in the case of a double-ended 10 boiler (see Fig. 5) the blower may be attached to one of the smoke tubes themselves; in both cases the tube a in which the blower is inserted is arranged in the center of the group of smoke tubes concerned.
- 15 A blower according to the present invention possesses considerable advantages as compared with those heretofore proposed. Thus in comparison with prior blowers having a fixed casing, the present invention is 20 simpler in construction and more easily operated while embodying an arrangement of orifice better adapted for the purpose in question. Moreover, as compared with blowers having a movable casing, the present 25 invention is distinguished by its greater simplicity and by its absolute safety in working, more especially as regards the prevention of any escape of steam or hot gases in the direction of the attendant. If the hollow 30 spindle instead of being provided with only one orifice is provided with two or more such orifices inclined at different angles to the longitudinal axis of the spindle, the fluid strikes the tubes under extremely 35 favorable conditions and a very effective cleaning action is insured.

In the above description it has been assumed that steam is used as the pressure medium and this in general will be most 40 convenient; it is, however, obvious that any other suitable gaseous pressure medium, such for instance as compressed air, may be employed if desired.

Having now particularly described and 45 ascertained the nature of my said invention and in what manner the same is to be performed, I declare that what I claim is:

1. In a blower device for cleaning tubes, in combination, a hollow spindle having a 50 nozzle orifice at one end thereof and a separate inlet aperture, a collar upon said spindle adjacent to the inlet aperture upon the side toward the nozzle orifice, a fixed casing having walls which are spaced from and constitute a steam tight closure about the said inlet aperture and in which casing the spindle 55 may be axially moved, said casing being also provided with a seat against which the aforesaid collar may be abutted thereby closing 60 said inlet aperture, and an inlet for said

casing adapted to be connected with a source of steam supply.

2. In a blower device for cleaning tubes in combination with a stationary casing having an inlet for the cleaning liquid to be supplied, of a spindle movably mounted in the casing and passing therethrough at both ends, said spindle being hollow at its forward end and having its rearward end screw threaded, a threaded boss on the casing engaging with the threaded end of the spindle, of an inlet port in said spindle, of a collar arranged around said inlet port, a correspondingly formed portion in the casing against which the afore-named collar abuts thereby closing the inlet port, when the spindle is in its rearmost position, and a discharging orifice at the forward end of the spindle.

3. In a blower device for cleaning tubes in combination with a stationary casing having an inlet for the cleaning liquid to be supplied, of a spindle movably mounted in the casing and passing therethrough at both ends, said spindle being hollow on its forward end and having its rear end screw threaded, a threaded boss on the casing engaging with the threaded end of the spindle, of steam-tight joints on each end of the casing, of means for actuating said spindle, of an inlet port in said spindle, of a collar arranged around said inlet port, a correspondingly formed portion in the casing against which the afore-named collar abuts, thereby closing the inlet port when the spindle is in its rearmost position, and a discharging nozzle on the forward end of the spindle.

4. In a blower device for cleaning tubes in combination with a stationary casing having an inlet for the cleaning liquid to be supplied, of a spindle movably mounted in the casing and passing therethrough at both ends, said spindle being hollow on its forward end and having its rearward end screw threaded, a threaded boss on the casing engaging with the threaded end of the spindle, of steam-tight joints on each end of the casing, of means for actuating said spindle, of an inlet port in said spindle, of a collar arranged around said inlet port, a correspondingly formed portion in the casing against which the afore-named collar abuts, thereby closing the inlet port when the spindle is in its rearmost position, and of a plurality of orifices inclined at different angles to the longitudinal axis of the spindle.

HERMANN ZEITZ.
